METHOD OF AND MACHINE FOR PRINTING ON COLLAPSIBLE ARTICLES

William F. Grupe, Lyndhurst, N. J., assignor to Peerless Roll Leaf Company, Inc., Union City, N. J., a corporation of New Jersey

Application February 9, 1954, Serial No. 469,143

13 Claims. (Cl. 101—44)

This invention relates to a method of and machine for printing on collapsible or flexible articles such as hollow containers.

At present, according to common practice, and as described in Patent No. 2,491,947, flexible bottles are mechanically crushed, thus enabling a flat die to imprint a design on one side.

As the die is raised the crushing means release the container, permitting it to expand to its normal wall position. If a second or more colors are to be applied to the reverse side, the container must be crushed for each color.

There are no means available to insure the same crushed position of the walls in relation to one another on the bed to insure close, accurate imprinting of each color in register to another to create a clean design. The crease or fold positions of the container may vary with each crush. Pursuant to this invention, the container is evacuated to bring the walls or sides of the container into parallel contact with one another, thereby materially reducing the hazards of marring or breaking down of the structure of the walls of the bottle that occurs when the bottles are mechanically crushed.

In the stamping operation, after the first color has been applied the bottle can be moved into progressive positions for other colors on either side with no variation possible, due to the fact that the two walls are held in mechanical contact with one another, resulting in practically a solid single structure to take the subsequent impressions.

In addition, to further insure accuracy of register, guide fingers may be provided to hold or locate the bottom end of the container—that is, the end remote from the mounting end.

The method of the invention enables the automatic printing of collapsible articles in an accurate and efficient manner. Pursuant to the method of the present invention, the article to be printed is positioned in a machine and indexed therein from station to station for progressive printing operations performed at predetermined stations. A number of stations may be provided in the machine, at one or more of which one face of the article may be partly or fully printed; at other stations the printing of said face may be completed or the other face of the article may be printed. Both faces may be partly or fully printed at one station.

By way of illustration only, if six stations are provided, the article may be automatically indexed from the first, or loading station, to four printing stations, and then to a final discharge station. In the example just stated, all four printing stations may be utilized for simultaneous or successive printing on one or both faces of the article.

Pursuant to the present invention, a rotor or hub is provided in the machine for carrying the articles to the stations therein, and means are provided for moving the rotor into serial registry with stations in the machine. Die members and opposed bed members are disposed at certain stations, and means are provided for moving the die and bed members toward opposed faces of the article

2

at such stations for performing the printing operation thereon. A vacuum means is preferably provided so that, while the printing operations are performed, the article will be held under vacuum.

5 Pursuant to the present invention, a rotor is provided and is disposed for axial movement in a given plane in the machine, and the article to be printed is secured to the rotor or to a holder fixed to the rotor. The rotor is serially indexed in the machine in a station-to-station arrangement which will automatically register the article to be printed in line with the printing units disposed at stations of the machine. Means are provided, synchronized for automatic action at such stations in timed relation to the stop-start sequence of movement of the rotor, to move the bed or die members (or both) at such stations onto the article to be printed. The rotor is provided with means to exhaust the interior of the article so that it will be essentially drawn down to a solid thickness defined by the walls thereof which would normally be spaced apart. The article is maintained under vacuum at the printing stations and may there be printed with successive complementary indicia to thus progressively print the article. Such arrangement will be found convenient, for example, in printing complementary indicia areas on the article, such as complementary overlapping or blending indicia, as well as indicia areas of different color. The range of printing variants possible pursuant to the invention will be found to be practically infinite. In the drawings:

30 Fig. 1 is an en elevational view, partly fragmentary, the one form of machine embodying the invention.

Fig. 2 is a perspective view of one of an infinite variety of forms of articles which may be printed pursuant to invention.

35 Fig. 3 is a partly sectional front elevational view of said machine taken on line 3—3 of Fig. 1.

Fig. 15 is an enlarged sectional view taken on line 15—15 of Fig. 13.

In the drawings a machine is shown by way of example only illustrating certain embodiments of the invention incorporating the invention. It will be apparent from the disclosure herein that the invention may be embodied in other machines. The machine 10 (Fig. 1) shown in the drawings, comprises a frame having horizontal supports 11 and 12 and vertical end supports 13, 14, as shown in Figs. 1 and 3. The center portion of the machine may be provided with suitable supporting base members 15—16 (Fig. 3) for further support of certain parts (such as a

vacuum line member and "Geneva" movement, more particularly described hereinafter).

Pursuant to the present invention, a rotor or hub 20 is provided, to which articles of any type to be printed may be secured, to be carried thereby to the respective stations of the machine. Station-to-station movement of the rotor may be obtained by suitable means such as, for example, a "Geneva" or other index or escapement wheel 22 (Fig. 3) actuated intermittently by a "Geneva" driver 23, or the like, which may be driven from a suitable source, such as indicated by the chain 24 connected to a motor or other source (not shown). Any suitable clutch means may be interposed between the chain 24 and the driver 23. For example, chain 24 may be keyed to one part 25 of a clutch, the other part 26 of said clutch being keyed to the shaft 27 to which the driver unit 23 may be keyed.

The vertical end supports 13-14 of the frame may be further connected, as indicated at 31-32 in Fig. 3, by a medial tie bar 30 (Figs. 4 and 12). The rotor 20 is preferably journaled on the bar 30; suitable bushings 33, 34 (Fig. 3) may be disposed intermediate the rotor 20 and the tie bar 30 to permit the rotor to freely rotate upon the latter. A spacing collar 35 may be keyed to the tie bar 30 as at 36, at one side of the rotor 20, and a vacuum line casing 37 may be formed unitarily with, or secured to, the center supporting base 15 at the other side of the rotor. The vacuum line casing 37 (see Figs. 11 and 3) is provided with a port 38, one end of which may be connected by means fragmentarily indicated at 39 (Fig. 11) to a suitable vacuum source, such as a pump (not shown). The other end 28 of the port 38 opens into an arc recess 40 on flat face 60 of casing 37. The rotor 20 is provided with a plurality of hollow rods or other flexible container holders 41-44 (Fig. 12), the free ends of which are adapted to have the articles 21 positioned thereon or secured thereto as shown in Figs. 5 and 4, for rotation with the rotor 20 to the respective stations of the machine as for example, marked in Fig. 5 and hereinafter more particularly described.

As shown in Figs. 4 and 5, the rotor 20 is keyed to the escapement wheel 22, the latter being provided with conventional radial slots to be engaged by the roller of the driver 23 (see Fig. 5) to progressively move the flexible containers 20 from station to station. It will be appreciated that, by varying the number of slots in the escapement wheel 22, or by similar expedients, the rotor 20 may be moved to a greater or lesser number of stations in the machine, as desired.

In the form shown in Fig. 5, for illustration only, there are six stations, of which one would be the leading station (#1 in Fig. 5), another the discharge station (#6 in Fig. 5) and intermediate printing stations (Nos. 2-5, for example). By this arrangement, indicia of one color or of a plurality of colors, for example, may be applied to one or both of the faces of the flexible container progressively or alternately at the printing stations of the machine.

The printing operation may be performed by any suitable means—for example, as shown in Figs. 4 and 8, by the use of a die 46 disposed in line with one face of the object 21 to be printed and bed 52, disposed at the opposite face thereof. The means for mounting the die and bed may be varied from the specific examples shown in the drawings, as will be apparent from a consideration of the drawings and the following description thereof, without departing from the invention.

In Fig. 8 the die 46 is shown secured to frame 45 provided with a handle 54 for facility of manipulation. Said frame 45 has formed unitarily therewith or secured thereto in any desired or convenient manner, the die block 50 having heater elements 47 and thermostatic control 48 (Fig. 9) said die block being secured to the base plate 53 preferably by means which will permit the position of the die 46 to be adjusted toward and from the bed 52, for adjustment of the pressure on the die. Said means may, as shown in the drawings, comprise bolts 81 whose heads

are seated in recesses in plate 53, said bolts (Fig. 8) passing freely through slots (not shown) in the clamping wedge 82 and into engagement with threaded apertures in the die block 50. The wedge 82 is positioned intermediate the front wall 84 of the base plate 53 and the die block unit 50, so that movement of said wedge intermediate the wall 84 of plate 53 and the block 50 will serve to adjust the position of the die 46, as will be apparent from an examination of Fig. 8, the bolts 81 serving as means of securing the parts in that position. The clamping wedge 82 is, in turn, so moved intermediate members 84 and 50, and held in adjusted position, by bolt or other means carried by the member 84 and engaging the clamping wedge 82 (see Fig. 8).

It will be apparent that a similar arrangement may be conveniently also used in connection with the bed 52, which may be made of a flexible, rigid or semi-rigid material yieldable under impact if desired, and which is secured by any suitable means, such as the frame 56 secured as at 57 (Fig. 4) to the frame 45' (which may be considered to correspond generally with frame 45). Frame 45' is provided with a handle 55 for facility of manipulation.

Said frame 45' has formed unitarily therewith or secured thereto, in any desired or convenient manner, the bed block 50' (said bed block may have heater and thermostat elements corresponding with 47 and 48 of block 50 formed therein so that when desired, block 50' could be heated and used as a mount for a die member instead of the bed 52). The block 50' is secured to plate 53' preferably by means indicated at 81', passing freely through slots in the clamping wedge 82' and into engagement with threaded apertures in the block 50'. The wedge 82' is positioned intermediate front wall 84' of plate 53' and the block 50', movement of the wedge 82' (comparable to that of wedge 82 described) enabling the adjustment of bed 52 relative to die 46, the wedge 82' being held in adjusted position by means 49'.

Pursuant to the present invention, the hollow rods or other container holders 41 are secured at their lower ends to the rotor 20 (Fig. 11) wherein they communicate with ports 61 which open onto the outer flat face 58 of the rotor 20 in radial registry with the arc recess 40 of the vacuum line casing 37. The outer ends of the ports 61 may be provided with rings 62, 63 spring urged as at 64 into sliding contact with the face 60 of casing 37.

Referring to Fig. 4, which is a partly sectional, elevational, horizontal view taken on line 4-4 of Fig. 3, it will be noted that the machine shown in the drawings, as exemplifying one form of the invention, is divided into three major parts as follows: two movable frames 66 and 68 (comprising respectively the generally circular plates 67 and 69, to which the bed and chase units for the respective printing stations of the machine are secured) and the rotor 20 rotatable therebetween. In the case of a machine having four printing stations as shown in Fig. 5, the respective bed and die units for said stations of the machine would be secured to the inner plate 67 of the frame 66 (in the illustration of Fig. 4, this would be the right hand frame in the machine). Frame 68 for the other—left hand—side of the machine, comprises, as shown in Fig. 4, inner plate 69 generally comparable to plate 67.

It will be appreciated from the foregoing that the inner plates 67, 69, carry the complementary chase or bed units, which, when brought together and onto the flexible containers 21 carried therebetween by the rotor 20, perform the printing operations at the respective printing stations of the machine.

Pursuant to the invention, means are provided for actuating the inner plates 67, 69 (and thereby the chase and bed units) toward each other and against the opposite faces of the flexible containers 21 brought into selective registry with the printing stations of inner plates 67, 69, at which the opposed units 53-53' are disposed,

to perform the printing operation. Rotor 20 is actuated to intermittently advance the flexible containers 21 to registry with the respective stations of the machine. Thus, for example, assuming station 1 (Figs. 4 and 5) to be the loading station of the machine, the flexible container would be positioned on the free end of rod 41 which is fixed to the rotor 20 by force fitting the open neck portion of the container over the free end of rod or by otherwise securing the same thereto.

If the machine, as shown in Fig. 5, is set up for four printing stations, it will have six stations in all, of which two (the loading and discharge stations) may conveniently be non-printing, and in that case there would be six container holders or hollow rods (Fig. 12 omits the fourth and sixth rods which would be opposite the numbers 42 and 43). The rods are fixed to and hence rotate with rotor 20, so that they will connect with the vacuum source only when the rod ports 61 at the face of rotor 20 register with arc recesses 40 on the flat face 60 of the fixed vacuum line casing 37. Thus the objects 21 fixed to the rods are not in vacuum at the loading station; the leading edge of vacuum recess 40 is disposed intermediate that station and the first printing station (Fig. 12). Thus, by the time the object 21 arrives at the first printing station (from the loading station) it will have been connected to the vacuum system and be under vacuum; it is maintained under vacuum from then until just before reaching the discharge station, when the port 61 for the rod carrying the object 21 will have reached the end of vacuum recess 40. At the discharge station of the machine the object will no longer be under vacuum.

At station No. 2 the first printing operation might take place. That printing operation may be performed with the use of suitable printing mechanism such as, for example, shown in Fig. 5 of the drawings, wherein a roll leaf hot stamping printing mechanism is shown associated with the printing die 46, for printing on one face of the flexible container and against the bed 52 of the opposite unit 53 of the machine. The particular printing mechanism used may be of any suitable type with which the invention may be conveniently employed. The form of the said printing mechanism, shown in detail in Fig. 5, for association with the die 46, is generally designated by reference character 70 and comprises (as further shown in Fig. 13) a supply roll 71 of roll leaf 72 which is wound by the driving reel 73 across the rods 74, 75 which guide the roll leaf 72 across the face of the die 46 and keep it normally spaced therefrom. It will be appreciated, from observing Fig. 13, that if the entire printing mechanism 70 is moved toward the bed 52, the roll leaf 72, being yieldable, will flex slightly while the die 46 presses the roll leaf onto the container 21 as shown in Fig. 4.

This operation will print the matter outlined by the die onto the container in the color of the roll leaf 72, as will be readily appreciated. This operation may be repeated at the successive printing stations of the machine and by this means successive colors (or successive die impressions of the same color) may be printed on one or both sides of the flexible containers 21. Suitable means may be provided for intermittently advancing the roll leaf 72 across the guide rods 74, 75 (and therefore across the die 46). Such means may for example, as shown in Fig. 13, comprise an air or other power source cylinder 76 actuating the rack 77 into engagement with a pinion 78 (Fig. 15) keyed to the shaft 79 of driving reel 73, the roll leaf 72 passing between and being driven by the feed roll 73 and the matching feed roll 73a, which may be of rubber and may be maintained against roll 73 under spring tension or otherwise. The roll leaf passes the reform for discharge in the direction indicated by the arrow 122.

Supplementary means may be provided for assuring accurate registration of the containers 21 with the printing die and bed members at the printing stations of the machine. One form of means suitable for this purpose

is shown in Figs. 9 and 10. It will be readily understood, from a description thereof, that other means, suited to the same end, may be substituted pursuant to this invention. As shown in Figs. 9 and 10, the registering means may comprise a pair of centering fingers 85, 86 keyed to pinions 89, 90, pivoted as at 87, 88, for example, so that the fingers will move in unison to their open position shown in Fig. 10 or closed position (into engagement with container 21 to center the latter) as in Fig. 9. Rotation of the pinions, 89—90 may be obtained by any suitable means, as for example, by keying link 91 to one of said pinions, the free end of said link being engaged by a pin 92 carried by the other unit. The pin 92 may be spring actuated as shown in Fig. 9 so as to preclude harsh or excessive movement of the fingers 85, 86. Pin 92 is secured to one of the units and fingers 85, 86 to the other. On movement of members 53—53' toward each other, the pin 92 will engage the free end of the link 91 and cause the fingers 85, 86 to move together and onto the container 21 to thus center the same intermediate the die and bed members 46, 52. Any suitable means may be provided to normally hold the fingers 85, 86 in their open position shown in Fig. 10, as for example, by providing a spring 93 engaging the link 91 and urging the same to the position at which said fingers will be open. Upon movement of the units 53—53' apart, the fingers 85, 86 will likewise automatically move apart, releasing the flexible container 21 for rotation to the next station of the machine.

Pursuant to the invention, means are provided for moving the center plates 67, 69 (Fig. 4) together for the printing operation, and then apart, to release the flexible containers from the printing elements, all in timed relation to the movements of the rotor 20. Said means for moving the inner plates 67, 69 toward and away from each other may be of any suitable construction, and may, as shown in the drawing, cooperate with the bearing shaft 30 which is fixed at its free ends 31, 32, to the end supports 13, 14, said shaft constituting a bearing for the inner plates 67, 69 and associated parts. The latter, as shown in Fig. 6, comprise, for each of the plates 67, 69, journal members which will facilitate slideable movement of said plates on the bearing shaft and further means to key the plates against movement at right angles to the longitudinal axis of the shaft. For the purpose just described, the inner plate 67 is coupled to outer slide plate 96 (Figs. 3 and 6); likewise inner plate 69 at the left hand side of the machine is coupled to an outer slide plate 97. Plates 67, 96, are secured together by the elongated collar 98 which may be fixed to said plates as indicated at 99 (Fig. 6). Suitable bearings 100, may be interposed between collar 98 and shaft 30 to insure free sliding movement of the frame 66 on said shaft. Movement of the inner plate 67 on the shaft as generally indicated by the arrow 101 of Fig. 6 is attained by suitable means such as links 102, 103 (Fig. 4) connected as at 104, 105 with the inner plate 67, and connected at their opposite ends 106, 107 to the ends 108, 109 of links 110, 111 connected as at 112, 113 to the vertical end support 14.

It will be apparent, from a consideration of Fig. 4, that, since the vertical end support 14 is fixed, any movement of the points of connection 114, 115, of the links 102, 103 with links 110, 111 will cause the inner plate 67 to reciprocate as indicated by arrow 101 of Fig. 6. Such movement of the points of connection of the links may be obtained by any suitable means, to thus move the inner plate 67 and thus the die 46 toward and away from the flexible container 21 at the predetermined times required for the printing operation. For example, the free ends of a forked bracket 116 (Figs. 5 and 4) may be connected with said pivot points 114, 115, the stem 117 of said bracket (Figs. 5 and 6) being connected to the plunger 118 of a cylinder 119 which is pivoted as

at 120 on the support 121 on which the machine is mounted.

By use of any suitable control means (not shown) the plunger 118 of the cylinder may be reciprocated in timed synchronism with the cycles of movement of the rotor 29 so that the inner plate 67 may be reciprocated at the times desired for the printing or other operations at the respective stations of the machine above mentioned.

The plate 69 for the left hand side of the machine (Fig. 4) may be provided with corresponding links and associated parts (which are given the same reference characters as those associated with frame 67). The lower ends 123, 124 of the frame plate 67 (a similar arrangement may be used for the left hand plate 69 of the machine) are preferably keyed for sliding on the guide-way or spline bar 125 to preclude accidental rotation of the frame 66.

The flexible containers may be initially inserted at station 1 of the machine onto the rods 41 by hand or by any suitable means such as, for example, by providing an automatic feed mechanism as shown in Fig. 1, comprising a plurality of spaced vertical rods 128 which guide the flexible containers 21 for vertical stacking. The containers are ejected from mechanism onto the rods 41 by any suitable means such as the ejector finger 129 which may be reciprocated by the plunger 130 actuated by a solenoid or the like (not shown).

The die and bed members 46, 52 may be secured to the chase and bed units, 53, 53' (Fig. 3) which in turn may be pivoted at one end 131 (Fig. 6) on the sliding frames 66, 68. The other ends of said units may be pivotally connected, as at 126, to connected link members, 132, 133. The connected link members 132, 133 in turn may be connected as at 134 to the outer plate 96 of the frame 66 (or similar arrangement may be used with plate 97). The links 132, 133 may be connected as at 135 to a secondary point of connection defined by a latch 136 whereby said links may be connected in a straight line as shown in Fig. 3 and 6 to dispose the units 53, 53' in proper position in the machine, or the said links may be moved to an out-of-line position such as shown in Fig. 7. Said latch 136 may be of any suitable form, such as for example is shown in Fig. 14 to comprise a spring actuated pin 140 adapted, on registration of the links, to be received in a recess 141 in link 132. The pin 140 may terminate exteriorly in a head 142 and normally held atop housing 143 in which the pin 140 is movable.

To disengage links 132, 133, the pin 140 is retracted from recess 141; the handle 144 of the link 133 may then be grasped to break the straight line connection of the links as shown in Fig. 7. This position of the links results in a tilting of the unit 53 to facilitate the insertion or removal of the die or bed members therefrom.

The present invention, as will be apparent from a consideration of the foregoing description and the appended claims, is directed, broadly, to the printing, in successive printing stages of plastic articles which are collapsible. The invention is not limited to the specific means shown in the drawings by way of example only for attaining this end result, nor is it limited to containers or other types of plastic articles. The invention is adapted to be broadly applied in the plastic field to the printing of articles which may be collapsed. Wherever herein used, such terms as "articles," "containers" and the like shall not be deemed in any way to limit the invention to any specific class of objects. The term "plastics" as used herein shall not be deemed to limit the invention to presently known plastic materials or products, the invention being broadly applicable to all collapsible articles, without limitation as to their form or to the material of which the same may be made.

The device herein described may be used to imprint multi colors on containers by the method set forth in the application filed under Ser. No. 352,865 on May 4, 1953,

entitled "Method of Printing Blown Bottles" wherein I am the applicant.

Having thus described my invention, what I claim as new and desire to secure by Letters Patent is:

- 5 1. Apparatus for printing indicia on open-mouthed containers of the type having a base and flexible side walls, comprising a movable carrier having a plurality of container closures, each constructed to receive and support one of the containers, a container printing station beside the carrier, stop motion drive mechanism for operating said carrier to bring said closures successively into register with said station, means including a vacuum duct through each closure for impressing a vacuum on each container as it is disposed at the printing station, to thereby move the container walls into contact with each other so as to present, essentially, while under vacuum, a single thickness combined wall to take the printing impression, printing impression means at said station including cooperating printing members, at least one of which is yieldable, and intermittently operated mechanism synchronized with said carrier stop drive mechanism for moving said printing means against said articles while they are so disposed at the printing station under vacuum.
- 10 2. In an apparatus as set forth in claim 1, said container printing station comprising a yieldable printing bed at one side of the carrier and a printing die at the other side thereof and aligned with the bed, said bed and die being so moved against opposite sides of the article so disposed at the printing station.
- 15 3. In an apparatus as set forth in claim 2, said bed and die being so moved simultaneously against opposite sides of the article so that said die may print thereon and being then moved away from said article, and means engaging the containers to hold them in registry with the printing die while the latter is moved thereagainst and disengaged from the container when the printing die is moved away therefrom.
- 20 4. In an apparatus as set forth in claim 1, said container closures comprising hollow tubes radially secured to the carrier and extending therefrom the containers being secured to the free ends of the tubes remote from the carrier.
- 25 5. In an apparatus as set forth in claim 1, one or more additional printing stations in said apparatus, and printing means at said first mentioned and additional stations for printing indicia of different colors onto the containers, said vacuum means holding the containers under continued vacuum at said printing stations and in movement between the printing stations so that multi-color impressions may be made on the containers.
- 30 6. In an apparatus as set forth in claim 1, additional printing stations in said apparatus, certain of said stations being located beside one side of the carrier and the others being located beside the opposite side thereof, and printing means at said stations, so that the containers may be imprinted on both sides thereof.
- 35 7. In an apparatus as set forth in claim 1, said printing station means at said station comprising a die member disposed beside a first side of the carrier and a yieldable bed member beside the opposite side thereof, and an additional printing station in said apparatus comprising a die member disposed beside said opposite side of the carrier at which the bed member of the first mentioned station is disposed, said additional printing station having a yieldable bed member disposed beside said first side of the carrier, whereby the container may have both faces thereof printed with indicia.
- 40 8. In an apparatus as set forth in claim 1, means at said printing stations for adjusting the positions of the die and bed members at said stations.
- 45 9. In an apparatus as set forth in claim 1, means at said printing stations for registering said containers therewith.
- 50 10. In an apparatus as set forth in claim 9, said means at said printing stations for registering said containers

therewith including fingers at said printing station and means to move said fingers into engagement with the container when the printing means are moved against the container for printing thereon and for moving said fingers away from said container to free the same after printing has occurred.

11. The method of printing indicia on open-mouthed containers of the type having a base and flexible side walls, comprising the steps of positioning a container on a closure member having a vacuum line therethrough, and imposing a vacuum on the container to move the walls thereof into contact with each other so as to present, essentially, a single thickness combined wall, and moving a printing means of a given color against one face of the container and a yieldable bed member against an opposite face thereof simultaneously, moving the printing means and bed member away from the container, moving the container between a second printing means of different color and a second yieldable bed member, while maintaining the vacuum in said container, and moving the second printing means and bed members against opposite faces of the container simultaneously, to thereby print indicia of different colors onto the container, while it is under vacuum.

12. In the method set forth in claim 11, the further

10

steps of holding the container in registered position with the first die member while the latter is moved thereagainst and again in holding the container in registered position with the second die means while the latter is moved thereagainst.

13. The method of printing indicia on open-mouthed containers of the type having a base and flexible side walls, comprising the steps of positioning a container on a closure member having a vacuum line therethrough and imposing a vacuum on the container to move the walls thereof into contact with each other so as to present, essentially, a single thickness combined wall, and moving printing impression means at least one of which is yieldable against the container while it is held under vacuum.
